ABSTRACT OF THE DISCLOSURE

Slide switch assembly having at least one reed switch and a magnet carrier slidably movable to a position to cause operation of the reed switch.

BACKGROUND OF THE INVENTION

In electronic instruments such as counters and the like, there is a necessity to provide switches to select certain functions in the electronic instrument. Heretofore, it has been a common practice to utilize rotary type switches for selecting such functions. However, it has been found that such rotary type switches limit certain dimensions of the electronic instrument and thus restrict the design of the packaging which can be utilized for such electronic instruments. There is, therefore, a need for a new and improved function selecting means for such instruments.

SUMMARY OF THE INVENTION AND OBJECTS

The slide switch assembly consists of a slide shaft. A block is slidably mounted on the shaft for movement longitudinally of the shaft. A magnet carrier is mounted on the block and a magnet is carried by the magnet carrier. A reed switch is mounted in a plane which is substantially parallel to the shaft. The reed switch is provided with elements which will move in the presence of a magnetic field to operate the same. Means is provided for shifting the block with the magnet carrier mounted thereon longitudinally of the shaft so that the magnetic field created by the magnet is moved into the vicinity of the switch to operate the same. A plurality of reed switches and a plurality of magnet carriers can be provided to greatly increase the functions which can be selected at one time.

In general, it is an object of the present invention to provide a slide switch assembly which takes very little space in one dimension.

Another object of the invention is to provide a slide switch assembly in which the same magnet carrier can be utilized to operate a plurality of reed switches.

Another object of the invention is to provide a slide switch assembly of the above character in which a plurality of reed switches can be operated simultaneously.

Another object of the invention is to provide an assembly of the above character in which a plurality of magnet carriers can be provided to permit the selection of multiple functions at one time.

Another object of the invention is to provide an assembly of the above character in which the magnet carriers can be mechanically interlocked to prevent the operation of certain reed switches by the carriers.

Additional objects and features of the invention will appear from the following description in which the preferred embodiment is set forth in conjunction with the accompanying drawing.

BRIEF DESCRIPTION OF THE DRAWING

FIGURE 1 is a front elevational view of an electronic instrument which includes a slide switch assembly incorporating the present invention.

FIGURE 2 is a bottom plan view looking along the

2

line 2—2 of FIGURE 1 with certain portions broken away.

FIGURE 3 is an enlarged cross-sectional view looking along the line 3—3 of FIGURE 1.

FIGURE 4 is a cross-sectional view looking along the line 4—4 of FIGURE 3.

DESCRIPTION OF THE PREFERRED EMBODIMENT

The electronic instrument which is shown in FIGURE 1 includes a cabinet or case 11 which is of a conventional width such as approximately 19 inches, but which is of a relatively shallow depth or short in height as, for example, 1 3/4 inches. The case 11 is provided with spaced parallel side frame members 12 having handle portions 12a. The case is also provided with a main front panel 13 which has a dress panel 14 and a glass panel 15 mounted therein.

The electronic instrument which is mounted in the case 11 is provided with indicator tubes 16 behind the glass panel 15 to provide a read-out. The indicator tubes 16 are mounted upon a printed circuit board assembly 17 of the type described in copending application Ser. No. 709,602, filed Mar. 1, 1968. Feet 18 formed of a suitable material such as rubber are mounted on the bottom side of the case 11. In addition, there is provided on the bottom front side of the case 11 a rod 19 which is pivotally mounted in a sleeve 20 carried by the bottom of the case. Detent means (not shown) is provided for retaining the rod 19 in the desired angular positions. The rod 19 is provided with bent end portions 19a which have rubber feet 22 mounted thereon. The rod 19 serves as a tiltable foot which, when it is moved to a forward position, serves to tilt the front main panel of the instrument upwardly above the surface of the table on which the instrument is resting. When the tiltable foot is folded back to an out-of-the-way position as shown in FIGURE 1, the instrument rests upon the feet 18 and the feet 22 are in an out-of-the-way position.

The main front panel 13 is provided with a lower portion 13a which extends the length of the instrument. A bottom trim strip 23 is secured to the lower portion 13a of the main front panel by suitable means such as screws 24. A plurality of spacers 26 are provided between the bottom trim strip 23 and the main front panel 13d and are held in place by screws 24. The spacers 26 are spaced along the length of the trim strip 23 so that there is provided a channel 27 which extends substantially the entire length of the main front panel but which is divided up by the spacer blocks 26.

Slide assemblies 35 which form a part of a slide switch assembly 36 are slidably mounted in the channel 27 provided in the main front panel as hereinafter described. The slide switch assembly 36 consists of a detent shaft or bar 37 which serves as a slide member and has a plurality of slide assemblies 35 slidably mounted thereon. The bar 37 is formed of a suitable non-magnetic material such as Delrin 500 or stainless steel. Each of the slide assemblies 35 consists of a bearing block 38 that has a recess 39 therein adapted to accommodate the upper side of the detent shaft or bar 37. Means is provided for removably securing the bearing block 38 to the detent shaft 37 and consists of a spacer plate 41 secured to the bearing block by a pair of screws 42 deposited on each side of the bearing block. With the arrangement shown, it can be seen that the bearing block 38 can be slid longitudinally of the shaft 37.

Detent means is provided for retaining the bearing block 38 in predetermined positions longitudinally of the shaft 37 and consists of a plurality of spaced tapered holes 46 in the shaft 37 spaced longitudinally of the shaft and

opening through one surface thereof. The tapered holes 46 are adapted to be engaged by a ball 47 carried in a bore 48 provided in the block 38 and yieldably urged into the tapered hole by a spring 49 disposed within the bore. With this detent means, as can be seen particularly in FIGURE 4, it is possible to position the bearing block 38 longitudinally of the shaft 37 in any one of a predetermined number of positions as determined by the spacing of the tapered holes 46 in the detent shaft 37.

Each of the slide assemblies 35 also includes a magnet carrier 51 which is secured to the bottom side of the spacer plate 41 by two of the screws 42. The magnet carrier 51 can be of various lengths. Thus, as shown in the drawing, it can be of a length which can carry one magnet or of a length which can carry two magnets. Each of the magnet carriers is provided with one or more magnet receiving recesses 52 which are spaced longitudinally of the magnet carrier and which face upwardly into the case 11. A pair of permanent magnets 53 are mounted in each of the recesses 52. The magnets are placed one above the other with the positive pole above the positive pole and the negative pole above the negative pole so that they oppose each other. The magnets are first held in place by a suitable material such as beeswax. Thereafter, the magnets are locked into place by means of a small piece of heat shrinkable tubing 54 which is slipped over the magnet carrier on the magnets and then, therefore, heated to shrink the tubing 54 to firmly retain the magnets in the recess.

Each of the slide assemblies 35 includes a switch arm 56 which is secured to the bottom side of the spacer plate 41 carried by the bearing block 38 by two of the screws 42. The switch arm 56 extends outwardly through the channel 27 provided between the main front panel 13 and the trim strip 23 and between a pair of the spacers 26. A knob 57 is mounted on the switch arm 56.

As can be seen from FIGURE 2, the slide assemblies 35 are either of the right-hand type or the left-hand type, depending on which side of the bearing block 38 the magnet carrier 51 extends.

A plurality of reed switches 61 are provided. The reed switches are mounted upon boards 62 of insulating material within the case 11 so that they lie in a plane which is substantially parallel to the shaft 37. The boards 62 are fastened within the case by screws 63. The reed switches 61 are of conventional type and are provided with a glass envelope 66 with a stationary element 67 and of a movable element 68 encapsulated therein. The elements 67 and 68 extend through the glass envelope and their ends serve as leads 69 which extend through the boards 62 and are connected to circuitry of a conventional type such as printed circuitry carried by the board. For example, the boards can carry logic circuitry or time base circuitry. The reed switches 61 can be either of the normally open or normally closed type.

As can be seen from FIGURES 2 and 3, the reed switches 61 are mounted on the undersides of the boards 62 so that the magnets 53 carried by the slide assemblies 35 can be moved into relatively close proximity with the reed switches so that the magnetic fields created by the permanent magnets can operate the switches, either by moving a normally open switch to a closed position or by moving a normally closed switch to an open condition.

As can be seen from FIGURE 2, the reed switches can be arranged in a plurality of rows as, for example, two rows 71 and 72 which are substantially parallel to each other. The reed switches in the row 71 are adapted to be actuated by the magnets carried by the single and double magnet carriers 51, whereas the reed switches 61 in the second row 72 are adapted to be actuated by the magnet carriers 51 which carry two sets of magnets.

It will be noted that one or more slide assemblies 35 are provided pairs of spacers 26. Thus, a single slide assembly 35, or two slide assemblies, or three slide assemblies 35 are provided pairs of spacers 26. Thus, a single

slide assembly 35, or two slide assemblies, or three slide assemblies are provided between certain pairs of spacers 26. The spacers 26 serve as front panel stops for the slide assemblies 35 and limit their movement longitudinally of the shaft 37.

Additional means is provided for limiting movement of certain of the slide assemblies 35 longitudinally of the shaft 37 and consists of rear stop means adapted to engage the rearmost extremities of the slide switches 36 which are provided with the magnet carriers for two sets of magnets. As shown in FIGURE 2, such means consists of a pair of spaced parallel strips 76 which are mounted upon posts (not shown) by means of screws 78. The strips 76 are aligned so that they are substantially parallel to the rows 71 and 72 of the reed switches 71. The spaced parallel strips 76, in addition to serving as stops for the magnet carriers 51, also serve to guide the movement of the magnet carriers so as to maintain the desired spacing between the magnet carriers and the reed switches.

Operation and use of the slide switch assembly may now be briefly described as follows. From the construction shown, it can be seen that each of the slide assemblies 35 can be moved longitudinally of the shaft 37 in spaced increments as determined by the spacing of the holes 46 provided in the shaft 37. The holes 46 are in exact alignment with the reed switches so that when the ball 47 is in registration with one of the holes 46, the magnet carrier 51 with the magnets 53 therein, underlies one of the reed switches 61 to operate the same if there is a reed switch in that position. Thus, it can be seen that as one of the slide assemblies 35 is moved along the shaft or bar 37, it operates a reed switch at approximately the time the ball 47 enters one of the holes 46 because in that position, the magnets carried by the magnet carrier immediately underlie the reed switch. If the slide assembly is of the type which carries two sets of magnets, the reed switch in each of the rows is actuated if there is a reed switch present in the row at the point to which the slide assembly has been moved.

It can be seen that various interlocks are provided to prevent the slide assemblies from being moved into positions in which they could possibly operate certain of the reed switches which should not be operated by that slide assembly. Thus, the spacers 26 provided in the front panel 13 serve as means to limit the movement of the slide switches on the bar 37. When one of the slide assemblies encounters a spacer 26, it can be shifted no further in that direction. Similarly, another slide assembly disposed within the same space between two spacers 26 cannot be moved beyond the slide assembly which is ahead of it or precedes it. In a similar manner, the rear stop means consisting of strip 76 prevents travel of the double magnet carriers beyond predetermined positions.

The bottom cover for the instrument shown in broken lines in FIGURE 3 of the drawing functions as a magnetic shield. The shaft or bar 37 which has been pointed out previously is formed of a non-magnetic material such as stainless steel. This prevents the shaft or bar 37 from distorting the magnetic field in the vicinity of the reed switches 61 even though it is in relatively close proximity to the reed switches 61.

It is apparent from the foregoing that there is provided a slide switch assembly which makes it possible to control functions in electronic instruments. It is particularly useful for such a purpose because the slide switch assembly and the slide assemblies forming a part thereof require very little space in a vertical dimension in the instrument, and thus make it possible to provide instruments which are very shallow in depth or short in height. Because of the interlocking arrangement provided, it is impossible to move such slide assemblies into unallowable conditions. The slide assemblies are also very versatile in that the front panel of the instrument can be color coded in that certain common areas through which cer-

tain of the slide assemblies travel can be coded in the same colors to indicate the operable areas. The slide assemblies provided are relatively simple and can be readily operated. As can be seen, they can be provided on the bottom section of the instrument so that ample room remains for the electronic parts of the instrument.

We claim:

1. In a slide switch assembly, a shaft, a block slidably mounted on the shaft for movement longitudinally of the shaft, a magnet carrier mounted on the block, a magnet mounted on the carrier, at least one reed switch mounted in a plane substantially parallel to the shaft, said reed switch having elements at least one of which is movable in response to the presence of a magnetic field, said block with said magnetic carrier being movable longitudinally of the shaft to position the magnetic field of the magnet carried by the magnet carrier to operate the reed switch.

2. An assembly as in claim 1 together with detent means carried by the block and the shaft for yieldably retaining the block in predetermined positions spaced longitudinally of the shaft.

3. An assembly as in claim 1 together with means for limiting the movement of the block between predetermined positions.

4. An assembly as in claim 3 together with additional means engaging the magnet carrier for limiting the movement of the magnet carrier between predetermined positions longitudinally of the slide member.

5. An assembly as in claim 1 wherein said magnet carrier carries a pair of spaced magnets and wherein additional reed switches are mounted in said plane substantially parallel to the shaft, said reed switches being arranged in parallel rows having substantially the same spacing as the magnets carried by the magnet carrier so that the reed switches in each of the rows can be energized by said magnets carried by the magnet carrier as the block is moved longitudinally of the shaft.

6. An assembly as in claim 5 together with additional blocks mounted on said slide member, a magnet carrier carried by each of said blocks, and at least one magnet carried by each of said magnet carriers, the magnet from said magnet carriers being aligned with said reed switches.

7. An assembly as in claim 1 wherein said reed switches are carried by a printed circuit board.

8. In a slide switch assembly, a slide member, a plurality of slide assemblies slidably mounted on said slide member for movement longitudinally of the slide mem-

5

ber, each of said slide assemblies comprising a block mounted on the slide member for movement longitudinally of the slide member, a magnet carrier mounted on each of said blocks, certain of said magnet carriers carrying a magnet at one position on said magnet carrier and others of said magnet carriers carrying spaced magnets on said magnet carrier, a support member, and a plurality of reed switches mounted on said support member, each of said switches having a pair of elements, one of the elements being movable by a magnetic field, said reed switches being arranged in spaced parallel rows having the same spacing as the magnets on said other of said magnet carriers whereby said reed switches are operated as said slide assemblies are moved longitudinally of the slide member.

9. An assembly as in claim 8 together with a front panel having a channel therein, each of said slide assemblies having an arm extending through said channel so that the slide assembly can be operated from said front panel.

10. An assembly as in claim 9 together with means for preventing movement of said slide assemblies beyond predetermined points on the slide member.

11. An assembly as in claim 10 wherein said means for preventing movement of said slide assemblies is mounted on the front panel.

12. An assembly as in claim 10 wherein said means for preventing movement of said slide assemblies includes means engaging the rear extremities of said other of said magnet carriers to limit the movement of said other magnet carriers longitudinally of the slide member.

13. An assembly as in claim 9 wherein said magnets are in the form of pairs of permanent magnets and heat shrinkable tubing for retaining said pairs of magnets on said magnet carriers.
